UNITED STATES PATENT OFFICE.

DAVID F. PROVANCE, OF NEW CASTLE, PENNSYLVANIA, ASSIGNOR TO BEAVER VALLEY GLASS COMPANY, OF ROCHESTER, PENNSYLVANIA, A CORPORATION OF PENNSYLVANIA.

DESIGN FOR A GLASS VESSEL OR SIMILAR ARTICLE.

48,081.

Specification for Design.

Patented Nov. 2, 1915.

Application filed January 7, 1915. Serial No. 1,052. Term of patent 7 years.

To all whom it may concern:

Be it known that I, DAVID F. PROVANCE, a citizen of the United States, and residing at New Castle, in the county of Lawrence and State of Pennsylvania, have invented a certain new, original, and ornamental Design Applied to a Glass Vessel or Similar Article, of which the following is a specification, reference being had to the accompanying drawing, forming a part thereof, wherein a superficially ornamented vessel is shown in elevation.

The superficial ornamentation embodying the design is of band form and consists of a multiplicity of fine thread-like etched lines which are white or opaque and are arranged to simulate a mesh or net. Above

and below the band-like mesh or net and adjacent to and paralleling the longitudinal margins thereof are the straight etched lines which are broader or heavier than the thread-like lines of the mesh or net formation.

The design is shown applied to a goblet of conventional form, the shape of which is not claimed.

I claim:—

The ornamental design applied to a glass vessel or similar article, substantially as shown and described.

DAVID F. PROVANCE.
